LINK CHAIN FOR A BRACELET OR SIMILAR ARTICLE

Yuen Sang Poon, Hong Kong, assignor to Yuen Sang
Hardware Co., Ltd., Hong Kong

Filed Nov. 13, 1970, Ser. No. 25,967

Term of patent 14 years

Int. Cl. D11—01

U.S. Cl. D45—4

FIG. 1.

FIG. 2.

FIG. 3.

FIG. 4.

FIG. 5.

FIG. 1 is a top plan view of a link chain for a bracelet or similar article showing my new design;

FIG. 2 is a front elevational view of FIG. 1;

FIG. 3 is a bottom plan view of FIG. 1;

FIG. 4 is a rear elevational view of FIG. 1; and

FIG. 5 is a perspective view, on an enlarged scale, of a portion of the link chain.

I claim:

The ornamental design for a link chain for a bracelet or similar article, substantially as shown.
